UNITED STATES PATENT OFFICE.

WILLIAM K. HENRY, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

THERMALLY-CONTROLLED DOOR CLOSER.

Application filed November 11, 1922. Serial No. 600,260.

My invention relates to door closers, and more particularly to door closing checks of the type which are capable of holding the door open when the door is opened to a predetermined degree, and of releasing and closing the door in the event of fire; and has for its principal object to provide a novel and improved door check of this type which is simple, strong and durable in construction, and reliable in operation.

The several features of the invention will be clearly understood from the following description and accompanying drawings, in which,—

15 Figure 1 is a plan view of a door check embodying the features of the invention in their preferred form, the door check being shown applied to a swinging door and the door case being shown in section;

20 Fig. 2 is a similar view but with the door shown open;

Fig. 3 is a side elevation of the same;

Fig. 4 is a detail sectional view, partly in elevation, taken on the line 4—4 of Fig. 2;

25 Figs. 5, 6 and 7 are detail sectional views taken on the lines 5—5, 6—6, and 7—7, respectively, of Fig. 4; and

30 Fig. 8 is a detail view in perspective of a fusible element constituting a component part of the door check.

The door check illustrated in the drawings is shown applied to a swinging door 2 and a door case 4. The door check comprises a casing 6 which is secured to the door. The casing 6 is of a common construction and contains a helical spring (not shown) surrounding the shaft 8. The spring is held under proper tension by means of a usual locking disk 10 mounted 35 on the upper end of the shaft, and a pawl 12 carried by the arm 14 and adapted to engage one of the notches 15 in the periphery of the disk. The actuating arm 14 is secured at one end to the upper end of the shaft 8 above the locking disk 10, and its free end is connected by a longitudinally adjustable link 16 with the door case. With this construction, upon opening the door the spring actuated arm 14 will tend to close the door and to hold the door closed 40 in the usual manner.

In the illustrated construction means is provided for holding the door open when it is fully opened or opened to a predeter-

mined degree. To provide for this a chamber 18 is formed on the under side of the arm 14 and extends longitudinally of the arm. The end portion of the interior of the chamber 18 directed toward the axis of the shaft 8 is reduced in diameter to provide a bearing for a slidable detent 20. An anti-friction roll 22, mounted on the outer end of the detent 20, is adapted to enter a cooperating locking recess or notch 24 in a projection 26 on the casing 6 when the door is swung open. The detent 20 is provided with a head 28 that cooperates with a shoulder 30 on the interior of the chamber 18 to limit the extent of the outward movement of the detent. The head 28 is U-shaped and the interior of the chamber 18 back of the shoulder 30 is of a corresponding shape so as to cooperate therewith to prevent the detent from turning, which insures the roll 22 being held in proper angular position at all times so as to enable it to properly engage the notch in the projection 26. The detent 20 is urged outwardly by means of a coiled spring 32 arranged in the chamber 18.

Except as hereinafter described, the parts above referred to may be and preferably are the same as the corresponding parts of the door check described and claimed in my pending application filed of even date herewith Serial Number 600,261.

In the illustrated construction the outer end of the coiled spring 32 is engaged by a movable abutment comprising a nut 34 which substantially fits the U-shaped portion of the interior of the chamber 18 so as to be held from rotation, but permitting longitudinal movement thereof in the chamber. An adjusting screw 36 for said abutment nut 34 is screw-threaded through the nut, and its outer end is provided with a head 37 that abuts a block 38 which is normally held in fixed angular position. The block 38 is provided with a central stud 40 that extends into a central socket in the screw head 36, and the stud is provided with an annular groove 42 through which a pin 44 secured in a transverse aperture in the head 38 extends, the pin being tangent to the inner periphery of the annular groove, thus providing a swivelled block on the head 37. This connection between the head of the adjusting screw 36 and the block 38

enables the screw to be turned to longitudinally adjust the abutment 34 without turning the block 38, and thus adjust the tension of the detent spring 32, the head of 5 the adjusting screw being provided with a series of radial sockets 46 so as to enable a socket wrench to be employed to turn the screw.

In the illustrated construction means is 10 also provided which is rendered operative only in case of fire for releasing the spring actuated arm 14 so as to enable it to close the door. To provide for this a flat, vertically disposed thermal device or fusible 15 member 48 is interposed between the block 38 and a fixed abutment 50 on the under side of the spring actuated arm 14. The fusible member is made up of two vertically disposed sheet metal parts which are 20 soldered or otherwise secured together by means of suitable fusible material 52. The block 38 is provided with a transverse slot 53 in which one end of the fusible member is seated, and the fixed abutment 50 is provided with a corresponding transverse slot 56 in which the other end of the fusible member is seated. The upper longitudinal edge portion of the fusible member is held 25 between depending lips 58 formed on the under side of the spring actuated arm 14. With this construction it will be apparent that in case of fire the fusible material connecting the component parts of the fusible member will become melted and the parts 30 separated, and as the fusible member serves as the abutment for the block 38, the screw 36 and abutment nut 34, the tension on the plunger spring 32 will be relieved, thus permitting the spring actuated arm 14 to immediately release its plunger 20 from the projection 24 and close the door.

From the foregoing it will be apparent that the fusible member is so mounted on the under side of the spring actuated arm 45 14 as to be well protected by the arm, and still be exposed to the maximum degree of heat of the room in which the door check is used.

As will be evident to those skilled in 50 the art my invention permits of various modifications without departing from the spirit thereof or the scope of the appended claims.

What I claim is:—

55 1. A door check having, in combination, a casing for attachment to the door, a spring actuated arm movable horizontally about the vertical axis of the casing, a slidable detent mounted on said arm and having one 60 end arranged to engage an abutment on said casing when the door is opened, a longitudinally slidable abutment mounted on said arm back of said detent, a coiled spring interposed between said slidable abutment and said detent, and a fusible member inter-

posed between said slidable abutment and an abutment on said arm and resisting the thrust of said slidable abutment.

2. A door check having, in combination, a 70 casing for attachment to the door, a spring actuated arm movable horizontally about the vertical axis of the casing, a slidable detent mounted on said arm and having one end arranged to engage an abutment on said casing when the door is opened, a longitudinally 75 movable abutment mounted on said arm back of said detent, a coiled spring interposed between said movable abutment and said detent, and a fusible member interposed between said movable abutment and an abutment on said arm and resisting the thrust of said movable abutment, said movable abutment having provision for adjustment to adjust the tension of said spring.

3. A door check having, in combination, a 80 casing for attachment to the door, a spring actuated arm movable horizontally about the vertical axis of the casing and having a longitudinally extending chamber on its under side, a slidable detent mounted in said chamber having one end arranged to engage an abutment on said casing when the door is opened, an abutment mounted for longitudinal movement in said chamber and held from rotary movement and arranged back 85 of said detent, a spring interposed between said movable abutment and said detent, an adjusting screw threaded through said movable abutment, a longitudinally movable block on which the head of the screw is 90 mounted for rotation, and a fusible member interposed between said block and an abutment on the under side of said arm.

4. A door check having, in combination, 95

a casing for attachment to the door, a spring actuated arm movable horizontally about the vertical axis of the casing and having a longitudinally extending chamber on its under side, a slidable detent mounted in said chamber having one end arranged to engage an abutment on said casing when the door is opened, an abutment nut mounted for longitudinal movement in said chamber and held from rotary movement and arranged back 100 of said detent, a spring interposed between said movable abutment nut and said detent, and adjusting screw threaded through said movable abutment nut, a longitudinally movable block on which the head of the screw is mounted for rotation, and means for holding said block from longitudinal movement in a direction away 105 from said spring and detent.

5. A door check having, in combination, 110 a casing, for attachment to the door, a spring actuated arm movable horizontally about the vertical axis of the casing, a detent mounted to slide longitudinally on said arm toward and from said axis of the casing and having one end arranged to engage an abut- 115

- ment on said casing when the door is open, an abutment mounted to slide longitudinally on said arm in the same direction as said sliding movement of said detent and arranged back of said detent, a coiled spring interposed between said slidable abutment and said detent, and a fusible member interposed between said movable abutment and an abutment on said arm and constituting an abutment for resisting the thrust of said slidable abutment, said detent, slidable abutment and fusible member being arranged in alinement. 55
6. A door check having, in combination, a casing for attachment to the door, a spring actuated arm movable horizontally about the vertical axis of the casing, a detent mounted to slide longitudinally on said arm toward and from said axis of the casing and having one end arranged to engage an abutment on said casing when the door is open, an abutment mounted to slide longitudinally on said arm, arranged back of said detent and held from rotary movement, 60
- 25 a coiled spring interposed between said slidable abutment and said detent for pressing the detent toward the axis of said casing, a screw screw-threaded through said slidable abutment, a fusible member arranged in alinement with said screw for resisting the outward thrust of said screw under the tension of said coiled spring, and a swivel connection between said screw and said fusible member to permit rotary movement of 65
- 30 the screw independently of said fusible member to vary the longitudinal position of said slidable abutment. 70
7. A door check having, in combination, a casing for attachment to the door, a spring actuated arm movable horizontally about the vertical axis of the casing and having a longitudinally extending chamber on its underside, a slidable detent mounted in said chamber having one end arranged to engage an 75
- 40 abutment on said casing when the door is open, an abutment mounted for longitudinal movement in said chamber and held from rotary movement and arranged back of said detent, a spring interposed between said 80
- 45 movable abutment and said detent, an ad- 85
- 50
- justing screw threaded through said movable abutment, and means for normally holding said adjusting screw from longitudinal movement but permitting rotary movement thereof. 90
8. A door check having, in combination, a casing for attachment to the door, a spring actuated arm movable horizontally about the vertical axis of the casing, a slidable detent mounted on said arm having its outer end arranged to engage an abutment on said casing when the door is open, a spring for urging said detent outwardly, and thermally controlled means for maintaining said spring under tension comprising a fusible 95
- member mounted on said arm and constituting an abutment for resisting the thrust of said spring, said means having provision for adjustment to vary the tension of said spring. 100
9. A door check having, in combination, a casing for attachment to the door, a spring actuated arm movable horizontally about the vertical axis of the casing, a slidable detent mounted on said arm having its outer end arranged to engage an abutment on said casing when the door is open, a spring for urging said detent outwardly, and thermally controlled means for maintaining said spring under tension comprising a fusible 105
- member mounted on said arm and constituting an abutment for said spring. 110
10. A door check having, in combination, a casing for attachment to the door, a spring actuated arm movable horizontally about the vertical axis of the casing, a slidable detent mounted on said arm and having its outer end arranged to engage an abutment on said casing when the door is open, a spring for urging said detent outwardly, 115
- 45 an abutment for holding the spring under tension, a screw on which said spring abutment is mounted for adjusting the position of the abutment to vary the tension of said spring and movable longitudinally with said abutment, and means comprising a fusible member for holding said screw and movable abutment from longitudinal movement against the action of said spring. 120
